(57) **CLAIM**

The ornamental design for a golf club head, as shown and described.

DESCRIPTION

FIG. 1 is a top perspective view of a golf club head;
FIG. 2 is a bottom perspective view of the golf club head of FIG. 1;
FIG. 3 is a top view of the golf club head of FIG. 1;
FIG. 4 is a bottom view of the golf club head of FIG. 1;
FIG. 5 is a front view of the golf club head of FIG. 1;
FIG. 6 is a rear view of the golf club head of FIG. 1;
FIG. 7 is a toe side view of the golf club head of FIG. 1;
FIG. 8 is a heel side view of the golf club head of FIG. 1;
FIG. 9 is a top perspective view of another embodiment of a golf club head;
FIG. 10 is a bottom perspective view of the golf club head of FIG. 9;
FIG. 11 is a top view of the golf club head of FIG. 9;
FIG. 12 is a bottom view of the golf club head of FIG. 9;
FIG. 13 is a front view of the golf club head of FIG. 9;
FIG. 14 is a rear view of the golf club head of FIG. 9;
FIG. 15 is a toe side view of the golf club head of FIG. 9;
and,
FIG. 16 is a heel side view of the golf club head of FIG. 9.
